MOLDED LADDER

Harold E. Morrison, San Francisco, Calif., assignor of one-third to G. B. Haynes, Los Altos, and one-third to D. R. McNeill, Jr., San Francisco, Calif.

Application July 13, 1953, Serial No. 367,710

3 Claims. (Cl. 228—18)

This invention relates to ladders and has for its main object the provision of a ladder that is very light in weight, yet strong and rigid, and which ladder is molded or cast from electrical insulation material.

Another object of the invention is the provision of a ladder adapted to be formed in a single molding operation from a composition material such as fiberglass and a suitable binder, and which ladder is so designed as to provide the maximum strength and maximum lightness in weight.

A still further object is the provision of an extension ladder that is very strong, light in weight and in which the sections forming such ladder are substantially of the same structure and so constructed and assembled that one ladder section guides the other during extension or retraction of one section relative to the other.

The use of fiberglass and a plastic is not new in itself. Automobile bodies, furniture, and other articles have been molded from such material, which is extremely strong and very light in weight.

The present structure provides a ladder that is capable of being formed in one molding step, and the parts of the ladder are so designed as to not only enable said molding operation, but to give maximum strength where required, together with minimum material for such strength. Inasmuch as the finished ladder is an excellent non-conductor of electricity, it is particularly suitable for linemen and for others that may find occasion to use the ladder where it would be dangerous to use ladders of other material.

Other objects and advantages will appear in the description and in the drawings.

In the drawings,

Fig. 1 is a fragmentary perspective view of a ladder made in accordance with this invention and showing the structure that contributes to the employment of the structure in making an extension ladder.

Fig. 2 is an enlarged sectional view taken along line 2—2 of Fig. 1.

Fig. 3 is an enlarged sectional view taken along line 3—3 of Fig. 1.

In detail, the side pieces of the ladder are generally designated 1, 2, and the rungs are designated 3. The side pieces and rungs are formed integrally in one piece, and each side piece comprises a vertically elongated channel member having sides 4, 5, and a curved bottom wall 6 (Fig. 2).

The remaining side is open and may be called the rear side since it would face away from the user when the ladder is in use.

The sides 4, 5 extend divergently relative to each other from bottom wall 6, and their inner surfaces 7 are preferably flat. The sides 4, 5 are progressively increasing in thickness along their free edges, as best seen at 8 in Fig. 2, which increased thickness along said edges serves to strength the side pieces. Otherwise the thickness of the material forming said sides is of uniform thickness, preferably of about one quarter of an inch, but this in-

2

vention is not restricted to such thickness for the ladder may be made of any dimensions found most desirable for the jobs to be done.

Each of the rungs 3 is also a channel member. Said rungs have laterally opening sides that are directed in the same direction as the open sides of the vertically extending side pieces 1, 2 when the latter are vertical.

The upper side 10 of each rung slants slightly upwardly in a rearward direction (the rear side being the open side 11 that is directed away from the user) and said side 10 is of progressively increasing thickness in said rearward direction.

The lower side 11 of each rung extends divergently relative to side 10 in a rearward direction and bottom wall 12 is curved transversely of the length of each rung and integrally joins sides 10, 11.

The side 11 of each rung curves downwardly (in a rearward direction) rather steeply from a point spaced slightly rearwardly of bottom wall 12, thus producing a generally vertically extending marginal portion 13 along the open side of each rung, which marginal portion acts like a truss for supporting weight in said rung.

The rungs 3 extend between the opposed sides 5 of side pieces 1, 2 and positioned between the sides 4, 5 of each side piece at each end of each rung is a web 15 (Fig. 2) that joins the sides 4, 5 of each side piece to materially stiffen and strengthen each of said side pieces.

Also, spaced along rungs 3 and between upper and lower sides 10, 11 of each rung are webs 16 integrally connecting said sides thus stiffening the rungs (Fig. 3).

The webs 15 that are between the sides 4, 5 of the side pieces 1, 2 are curved along their rearwardly directed free edges at the open sides of said side pieces, and as these webs are horizontal (when the side pieces are vertically extending), their curved rear edges extend horizontally. Said curved rear edges of the webs 15 substantially correspond to the horizontal cross sectional contour of the outer side of the bottom wall 6 of each side piece.

In an extension ladder, the upper section 20 (Fig. 1) and the lower section 21, have parallel, side pieces of the same spacing and are positioned so that the curved bottom wall 6 of the side pieces of the section extend between the walls 4, 5 of the side pieces of the other section and against the curved edges 17 of webs 15 thus said webs form guides slidably supporting the side pieces of one of the two sections. If it were not for said webs, the side pieces would jam one within the other, but with this structure they readily slide relative to each other.

The conventional straps 25 (only two are shown, there usually being another set spaced from these along the ladders) hold the ladder sections together. The usual supports in extension ladders (not shown) at the lower end of the upper one, serve to hold the upper ladder in extended position. No claim is made to such supports since they are old and are readily adapted to the present ladders.

From the structure shown, it is not only apparent that the ladder can be readily molded in one piece, but the structure that contributes to that result also contributes to strengthening the ladder and bracing the side pieces and rungs against any tendency to twist or to bend when the ladder is in use.

I claim:

1. In a ladder having elongated generally vertically extending side pieces disposed in a common plane in side by side horizontally spaced relation, vertically spaced rungs extending between and connecting said side pieces, said rungs being in the form of horizontally extending channel members having an upper side wall and a lower side wall and a bottom wall connecting them along one of their longitudinally extending edges and the sides of said

rungs opposite their bottom walls being open and generally directed perpendicular to said plane, the lower side wall of each rung being curved downwardly in cross sectional contour transversely of each rung and the upper side wall of each rung having a substantially flat upper side extending slightly upwardly relative to a horizontal plane in direction toward its free edge when said side pieces are vertical.

2. An extension ladder comprising a pair of ladder sections each having a pair of elongated parallel side pieces 10 equally spaced apart and with the side pieces of one section aligned with those of the other section in direction transversely of said sections, each of said side pieces being in the form of a channel having generally opposed side walls and a bottom wall connecting them along one of their free edges with their side opposite said bottom wall being open, the bottom walls of the side pieces of one pair extending into the open sides of the side pieces of the other pair, and means within the said side pieces of said other pair slidably engaging the said bottom walls that 15 extend into said open sides for sliding one of said ladder sections longitudinally thereof relative to the other and means connecting said sections for holding them together during such sliding, the open sides of the side pieces of said sections being directed laterally of the plane in which the side pieces of each section are disposed.

3. An extension ladder comprising a pair of ladder sections each having a pair of elongated parallel side pieces 20 equally spaced apart and with the side pieces of one section aligned with those of the other section in direction transversely of said sections, each of said side pieces be-

5

ing in the form of a channel having generally opposed side walls and a bottom wall connecting them along one of their free edges with their side opposite said bottom wall being open, the bottom walls of the side pieces of one pair extending into the open sides of the side pieces of the other pair, and means within the said side pieces of said other pair slidably engaging the said bottom walls that 10 extend into said open sides for sliding one of said ladder sections longitudinally thereof relative to the other and means connecting said sections for holding them together during such sliding, said means within said side pieces being webs connecting the side walls of said last mentioned side pieces reinforcing the latter, the open sides of the side pieces of said sections being directed laterally of the plane in which the side pieces of each section are disposed.
